CLAIM

The ornamental design for a rangefinder display screen as shown and described.

DESCRIPTION

FIG. 1 is a front view of a first embodiment of a rangefinder display screen showing our new design.

FIG. 2 is a front view of a second embodiment of the rangefinder display screen.

FIG. 3 is a front view of a third embodiment of the rangefinder display screen

FIG. 4 is a front view of a fourth embodiment of the rangefinder display screen.

FIG. 5 is a front view of a fifth embodiment of the rangefinder display screen.

FIG. 6 is a front view of a sixth embodiment of the rangefinder display screen.

FIG. 7 is a front view of a seventh embodiment of the rangefinder display screen.

FIG. 8 is a front view of an eighth embodiment of the rangefinder display screen.

FIG. 9 is a front view of a ninth embodiment of the rangefinder display screen; and,

FIG. 10 is a front view of a tenth embodiment of the rangefinder display screen.

The broken lines in FIGS. 1-10 depict portions of the rangefinder display screen that form no part of the claimed design.

1 Claim, 2 Drawing Sheets
